Application February 19, 1932, Serial No. 594,055,
and in Germany January 9, 1931

4 Claims. (Cl. 179—171)

I have filed an application in Germany, January 9, 1931.

The invention is concerned with a circuit scheme designed to compensate non-linear distortions, and the same is primarily applicable to amplifiers intended to supply more than the average power. What was expected of amplifier arrangements of the earlier art is that they should combine freedom from non-linear distortion with a maximum power output. This demand means poor utilization of the amplifier tubes, for the utilization is limited by the desired freedom from distortion.

In order to compensate such distortion as is ascribable to the knee in the characteristic curve, the idea has been practiced in the prior art to provide transfer elements, say, amplifier tubes, whose characteristic curve presented a contrary curvature or knee. However, schemes of this kind suffer from a fundamental drawback. They necessitate a very exact balancing of the characteristic curves of the tubes, and as a result they are highly sensitive to the replacing of circuit elements, most particularly of tubes. Another point is that with known circuit schemes stray or disturbing waves (line noises or hums) due, for example, to foreign sources of trouble which are not known beforehand and which may arise only temporarily, can not be readily compensated.

According to this invention, for the purpose of avoiding the said disadvantages, a basically different way is followed. What is used is what may be termed a "linearizing" scheme presenting a linear characteristic (say, an amplifier of low power) which is so controlled by the circuit arrangements to be freed from distortion and is so combined or connected therewith that the aggregation of currents or potentials furnished from the said linearizing scheme and the arrangements to be freed from distortion, will be free of all non-linear distortions. In these circuit schemes it is not necessary to know exactly the characteristic of the part causative of the distortion in order to proportion accordingly the characteristic of the linearizing scheme; in fact, it is sufficient for the linearizing means to present a linear form of characteristic.

By the coupling provided between the linearizing arrangement and the rest of the circuit arrangement the linearizing scheme, as it were, automatically adapts itself to the form of the characteristic of the part to be freed from distortion. Especially in the case of power amplifiers the invention makes it feasible to choose generators of maximum efficiency for the power

stages regardless of the question of distortion. As a result the circuit elements may be reduced to a minimum amount.

The invention is not only useful for amplifier arrangements, but generally wherever a compensation of non-linear distortions is required. The invention is suited for measuring arrangements just as readily as for the purpose of absorbing disturbing frequencies, especially in schemes in which the currents or grid potentials are improperly filtered or where the filament circuits are dissymmetric. Inside the scope of this invention it is immaterial in what particular way the non-linear distortions have been caused, i. e., whether it has been the curvature or knee of a tube characteristic or the knee in an iron-cored coupling means or that of a load-dependent resistance that is responsible for this condition. The invention insures freedom from undesired frequencies both in alternating current potentials as well as direct current potentials.

Fundamentally speaking there exist two ways and means of uniting the linearizing means with the distorting circuit arrangement. That is to say, the linearizing means and the distorting arrangement are either connected in parallel with the consuming device or load, or else the linearizing means, the distorting arrangement and the consumer are connected in series.

In the drawings, which will be used in the further explanation of my invention,

Fig. 1 is a generalized analysis of one form of the invention,

Fig. 2 is a generalized analysis of another form of the invention,

Fig. 3 is a curve showing the relation between certain elements of the network of Fig. 1,

Fig. 4 is a circuit diagram embodying the invention of Fig. 1,

Fig. 5 is a circuit diagram embodying the invention of Fig. 2.

In order to explain the basic idea of the invention there shall first be discussed the parallel scheme which is important in practice. For a discussion of the principle we shall regard the distorting arrangement and the linearizing means each as a generator connected conjointly with the consumer or load. Referring to Fig. 1, I denote the distorting generator briefly to be called the "power generator", and III denotes the linearizing generator, both being connected in parallel relation to the consumer or load Z. The assumption shall be made that the impedance of the consumer Z involves any complexity at all and that it is linear. The internal impedance R_1 of the

power generator shall not be constant, but always positive, in other words, generator I constantly delivers power. Owing to the change in the resistance R_1 with the load, non-linear distortions are produced. The object of the linearizing means is to render the aggregate current (J_1+J_3) flowing through the consumer Z independent of the alterations of the said resistance R_1 . The said aggregate current, in fact, should be a function only of the potential to be amplified, the control potential E_{g1} , and the properties of the linearizing generator III whose characteristic curve is presupposed to be linear. If the current J_1 delivered by the power generator is too small then the linearizing generator must furnish a correspondingly larger current J_3 . In other words, the generator III acts both as a generator as well as a consumer according to whether the internal resistance of generator I fluctuates upwards or downwards.

To explain the calculations hereinbelow made, this is a list of the symbols used:

E_{01} =separately controlled electromotive force of generator I
 25 E_{03} =separately controlled electromotive force of generator III (In all schemes $E_{01}=E_{03}$)
 E_1, J_1, R_1 =terminal potential, current and internal resistance of generator I
 E_3, J_3, R_3 =terminal potential, current and internal resistance of generator III
 39 A_1 =arbitrary constant
 =amplification factor (gain) of generator III (for all frequencies and amplitudes real and constant).
 55 The terminal potential of the power generator I is

$$E_1 = E_{01} - J_1 \cdot R_1 \quad (1)$$

where $J_1 \cdot R_1$ is the internal drop of potential of the generator.

The linearizing generator is so connected that the following potentials prevail at its grid:

$$E_{g1} = \frac{1}{v} \cdot E_{01} \quad (2)$$

$$E_{g2} = \frac{R_3}{v} \cdot J_3 \quad (3)$$

$$E_{g3} = -\frac{A_1}{v} \cdot (J_1 + J_3) \quad (4)$$

Whence a value for the terminal potential of the generator III is:

$$E_3 = E_{01} + J_3 \cdot R_3 - A_1 \cdot (J_1 + J_3) - J_3 \cdot R_3 \quad (5)$$

The first three members of Equation (5) correspond to the above mentioned grid potentials E_{g1} , E_{g2} and E_{g3} , whereas the last term represents the internal fall of potential of the linearizing generator. The portion E_{g2} of the terminal potential due to the grid potential, as will be noted, is equal and opposite to the internal drop of potential of the tube.

What follows from Equation (5) is:

$$J_1 + J_3 = \frac{1}{A_1} \cdot (E_{01} - E_3) \quad (6)$$

The integral current (J_1+J_3) flowing through the consumer Z, as will be seen, is a function only of the control potential, the terminal potential of generator III and the constant factor A_1 . In other words, the influence of the variable resistance R_1 is eliminated by a circuit scheme as here disclosed.

75 The operation and effect of the linearizing

means can be explained also by the aid of the following equations: From Equation (1) there follows:

$$J_1 = \frac{1}{R_1} \cdot (E_{01} - E_1) \quad (7) \quad 80$$

From Equation (6) this value is derived for the current of the linearizing generator:

$$J_3 = \frac{1}{A_1} \cdot (E_{01} - E_3) - J_1 \quad (8) \quad 85$$

Equation (7) introduced in Equation (8) and when putting $E_1 = E_3$ for a parallel circuit scheme results in:

$$J_3 = \frac{1}{A_1} \cdot (E_{01} - E_3) - \frac{1}{R_1} \cdot (E_{01} - E_3) \quad (9) \quad 90$$

or

$$J_3 = (E_{01} - E_3) \cdot \left(\frac{1}{A_1} - \frac{1}{R_1} \right) \quad (10) \quad 95$$

What may be seen from the last two equations is that the current of the linearizing generator comprises a component adapted to compensate the defect in the generator current J_1 . From Equation (10) there results furthermore that the current J_3 will be so much smaller the less the difference between A_1 and R_1 . This fact is important so far as the dimensioning of the linearizing factor is concerned. By suitable proportioning of the factor A_1 it is feasible to make conditions so that the linearizing generator furnishes almost as much current as is required for the purpose of compensating the distortions occasioned by the changes in the resistance R_1 .

The relation between J_1 and J_3 flows from the Equations (6) and (1):

$$J_1 + J_3 = \frac{1}{A_1} \cdot J_1 \cdot R_1 \quad (11) \quad 100$$

$$J_3 = J_1 \cdot \frac{R_1 - A_1}{A_1} \quad (12) \quad 115$$

Fig. 3 shows the generator current J_1 and the integral current $J_1 + J_3$ as a function of the potential $E_{01} - E_3$. The distance between the two curves measured in the direction of the ordinate axis, corresponds to or is a criterion for the current J_3 to be supplied by the linearizing generator. The constant angle of inclination of the line $(J_1 + J_3)$ is equal to A_1 , whereas the variable angle of inclination of the curve J_1 corresponds to the resistance R_1 .

For the series scheme shown in Fig. 2 for the two generators I and III there result similar relations as for the parallel scheme. The two schemes are reciprocal as to resistance. In what follows the same symbols are used as in the calculations covering the parallel connection. The terminal potential of the power generator I is again:

$$E_1 = E_{01} - J_1 \cdot R_1 \quad (13) \quad 120$$

In order to compensate the undesirable dependence upon R_1 the terminal potential E_3 of the linearizing generator III is in series with the terminal potential E_1 , the former containing the value E_1 as a negative term. In this manner perfect linearizing would be feasible if, similarly as in the parallel connection scheme, back-feed or regeneration is provided so that the internal potential fall of the linearizing generator will play no part whatever. However, the generator III would have to furnish a very large power, not to mention this fact that entirely unstable conditions would arise.

Now, in order to avoid this drawback the gen-

erator III is provided with another back-feed being proportional to the current $J_1 (= J_3)$, and this regeneration may be chosen so large that the linearizing generator will supply only as much current as is required for the compensation of the departure of resistance R_1 from its nominal value.

At the grid of the linearizing generator there prevail these three potentials:

$$E_{o1} = \frac{1}{v} \cdot E_{01} \quad (14)$$

$$E_{o2} = \frac{1}{v} \cdot E_1 \quad (15)$$

$$E_{o3} = -\frac{1}{v} \cdot (A_1 - R_1) \cdot J_1 \quad (16)$$

Hence, there results a terminal potential for the line arising generator as follows:

$$E_3 = E_{01} - E_1 - A_1 \cdot J_1 + R_1 \cdot J_1 - R_3 \cdot J_1 \quad (17)$$

where the first four terms represent the component ascribable to the three grid potentials, and the last term represents the internal fall off of the potential of the linearizing generator. The factor of the regeneration term proportional to J_1 has been so chosen that the internal fall off of potential of generator III does not appear at all. From Equation (17) there follows for the sum total of the two terminal potentials connected in series:

$$E_3 + E_1 = E_{01} - A_1 \cdot J_1 \quad (18)$$

The aggregate potential fed to the consumer Z , as will thus be noted, is independent of the properties of the generator I. From Equations (13) and (17) there results

$$E_3 = E_{01} - E_{01} + R_1 \cdot J_1 - A_1 \cdot J_1 \quad (19)$$

or

$$E_3 = (R_1 - A_1) \cdot J_1 \quad (20)$$

$$E_1 = E_{01} - R_1 \cdot J_1 \quad (13)$$

A comparison of Equations (20) and (13) goes to show in what way the influence of R_1 is compensated by the series connection of E_1 and E_3 .

Introducing the Equation (13) into Equation (18) there is obtained

$$E_3 + E_{01} - R_1 \cdot J_1 = E_{01} - A_1 \cdot J_1$$

From the equation for E_3

$$E_3 = (R_1 - A_1) \cdot J_1 \quad (20)$$

there results, similarly as for the parallel connection scheme, that the terminal potential of the linearizing generator becomes so much lower, the smaller the difference between A_1 and R_1 .

As stated at the outset the present linearizing scheme is adapted to compensate also foreign disturbing waves, which, therefore are not contained in the input potential E_{g1} . In the calculations these disturbing frequencies need not be taken into consideration inasmuch as they would produce similar effects as the distortions occasioned by alterations of the resistance R_1 . The same things that hold true of the calculations and the considerations made in connection therewith, apply also to the construction of the circuit arrangements, for also in the latter those disturbing frequencies need not be specially taken into account. The linearizing scheme compensates automatically all disturbances which arise within the power circuit arrangement between the input and the output ends thereof.

Now, Figs. 4 and 5 illustrate two embodiments of the basic idea of the invention by way of ex-

ample. Fig. 4 shows the power and linearizing generator connected in parallel, while Fig. 5 illustrates the series arrangement thereof.

In the case shown in Fig. 4 the power stage is represented by the two amplifier tubes V_1 and V_2 connected push-pull fashion. However, the linearizing scheme is not confined to the combination of such a push-pull stage, indeed, it may be used in combination with any other circuit arrangement.

Before the linearizing generator V_4 an amplifier tube V_3 is coupled by way of resistances and capacities, though this is not essential for the linearizing generator, in fact, the same is merely provided so as to insure proper phase relations, the latter being insurable also by other ways and means.

Across the input terminals K_1 and K_2 is connected the primary winding W_1 of an input transformer which has two secondary windings W_2 and W_3 .

By way of the secondary winding W_3 the input potential E_{g1} is fed to the grids of the two amplifier tubes V_1 and V_2 .

The same potential E_{g1} is applied also by way of the second secondary winding W_2 to the grid of the amplifier tube V_3 .

Included in the plate circuit of the power generator are the primary windings of the two transformers Tr_1 and Tr_2 and the ohmic resistances X and the choke coils Dr .

Connected with the series-connected secondary windings of the two transformers is the consumer or load device Z .

The output circuit of the linearizing generator V_4 is connected in parallel with the output end of the power transformer by way of the transformer Tr_4 .

In parallel with the series connection comprising the resistances X and the choke coils Dr is the primary winding of the transformer Tr_3 whose secondary winding

conjointly with the second secondary winding W_2 of the input transformer is connected in series with the grid of the amplifier tube V_3 .

The potential E_{g3} transferred by the transformer Tr_3 is proportional to the aggregate current $(J_1 + J_3)$ flowing through the resistances X and the choke coils Dr .

In the plate circuit of the linearizing generator V_4 , and in series with the primary winding of the transformer Tr_4 there is included a series arrangement R comprising an ohmic resistance and a choke-coil.

Across R is produced a fall of potential which is proportional to the plate current J_3 of the linearizing generator. This fall of potential E_{g3} by way of the condenser C_1 is applied also to the grid circuit of the amplifier tube V_3 .

The choke-coils Dr connected in series with the grid and plate batteries serve for precluding the alternating currents which are to flow by way of the condensers C_1 , C_2 and C_3 .

The inductance coils Dr and the inductance pertaining to series arrangement R are necessary inasmuch as the transformers are not ideal.

Some details of the circuit scheme which are not directly related to the linearizing arrangement have been omitted for the sake of simplicity.

For the same reason a distinct battery is shown for each plate and grid circuit.

The elements forming part of the series scheme illustrated in Fig. 5 have been designated similarly as in the parallel scheme in Fig. 4.

The power stage in this instance does not consist of a push-pull stage, but of a simple amplifier V_1 .

The input potential to be amplified, E_{g1} , is fed by way of terminals K_1 and K_2 to the input transformer comprising windings W_1 , W_2 , and W_3 .

By way of winding W_3 the input potential E_{g1} is fed to the grid of the power tube.

Through the winding W_2 the input potential E_{g1} is fed to the grid

circuit of the amplifier tube V_3 connected before the linearizing generator V_4 . The plate circuits of the power generator and the linearizing generator include the two transformers $Ir1$ and $Ir2$ whose secondary windings arranged in series supply the consumer device Z .

Assuming that ideal transformers are concerned the currents flowing in the plate circuits of the two tubes V_1 and V_4 are alike. Consequently also the fall of potential across the resistance R contained in the plate circuit of the linearizing generator is proportional to the consumer current $J_1=J_3$. In parallel relation to the resistance R is the primary winding of a transformer $Ir3$ whose secondary winding is connected in series with the winding W_2 of the input transformer in the grid circuit of the amplifier tube V_3 . Hence, by way of the transformer $Ir3$ a grid potential E_{g3} is applied to the input circuit of the linearizing scheme, said potential being proportional to the current in the consumer circuit.

The third grid potential E_{g2} which is proportional to the terminal potential of the power generator is fed by way of the condenser C_1 to the grid circuit of the amplifier tube V_3 . In the embodiment shown by way of example the said potential is tapped in the primary winding of the transformer $Ir1$, it being, of course, feasible to obtain this potential also in some other manner. In lieu of the condenser C_1 also a high ohm resistance could be used under certain circumstances. The choke coils $D'r$ and the condensers C_2 and C_3 have the same denotation and purpose as in Fig. 4.

35. What I claim is:

1. A distortionless amplification system comprising an electron discharge device amplifier having an input circuit and an output circuit,

means for inductively feeding waves to be amplified through the input circuit of said amplifier, a load circuit, means for inductively feeding amplified waves in the output circuit of said amplifier to said load circuit, an auxiliary electron discharge device amplification system having an input circuit and an output circuit, means inductively coupling the input circuit of said auxiliary amplifier to the input and output of said first mentioned amplifier, the coupling being so chosen that for a desired ratio of amplification of said first mentioned amplifier substantially no currents are fed to the input circuit of said auxiliary amplifier, and means for inductively coupling the output of said auxiliary amplifier to said load circuit whereby departure from said desired ratio causes currents to be fed into the input circuit of said auxiliary amplifier and causes amplified currents of said auxiliary amplifier to be fed into said load circuit from the output circuit of said auxiliary amplifier so as to maintain waves in said load circuit at a desired ratio to waves fed to the input circuit of said first mentioned amplifier.

2. Apparatus as claimed in the preceding claim wherein said first mentioned amplifier is in the form of a pushpull circuit and wherein neutralization means are provided to prevent oscillation generation of said auxiliary amplifier.

3. Apparatus as claimed in claim 1 wherein the output of said auxiliary amplifier is parallel with the output of said first mentioned amplifier for jointly feeding said load circuit.

4. Apparatus as claimed in claim 1 wherein the output of said auxiliary amplifier and the output of said first mentioned amplifier are serially fed into said load circuit.

WALTER HÄHNLE.
